UNITED STATES PATENT OFFICE.

JAMES E. CAMPBELL, OF GREENVILLE, MISSISSIPPI.

COMBINED OIL-CUP AND CIRCUIT-CLOSER.

1,209,553.

Specification of Letters Patent. Patented Dec. 19, 1916.

Application filed March 21, 1916. Serial No. 85,691.

To all whom it may concern:

Be it known that I, JAMES E. CAMPBELL, a citizen of the United States, residing at Greenville, in the county of Washington and State of Mississippi, have invented new and useful Improvements in Combined Oil-Cups and Circuit-Closers, of which the following is a specification.

This invention relates to a combined oil cup and thermostatic circuit closer by means of which a journal can be effectively oiled and upon cessation of the flow of oil and the resulting heating of the bearing, the circuit closer will be actuated for giving a signal.

The primary object of the invention is to provide a device of this character that can be readily inserted into place and accomplish the two results previously set forth.

Another object of the invention is to dispose a portion of the thermostatic circuit closer in a closed compartment so that the air in the compartment will be readily heated by the rising temperature of the bearing or in case of oil to have its temperature raised, this heat being concentrated around the thermostatic circuit closer.

A further object of the invention is the novel manner in which the mercury column of the circuit closer is effectively held against vibration during the operation of the machine to which the device is attached.

The invention consists in the features of construction, combination and arrangement of parts hereinafter fully described and claimed, reference being had to the accompanying drawing, in which:—

Figure 1 is a vertical section through a journal showing my device applied thereto. Figs. 2 and 3 are horizontal cross sections therethrough, and Fig. 4 is a view similar to Fig. 1 of a modified form of my invention.

Referring to the drawings, and more particularly to the preferred form of my invention, the numeral 1 designates a bearing in which is rotatably mounted an axle 2. This bearing 1 is provided with a bore 3 communicating with the axle 2, and mounted within the bore 3 and having screw threaded engagement with the bearing 1, as indicated at 5, is a tube 6 having its lower end closed and shaped to conform to the curvature of the axle 2. This tube 6 has its external diameter contracted from the point 7 to the bottom thereof so as to leave be-

tween the bore wall and the outer surface of the tube an annular channel 8 that communicates with the interior of the tube by way of an outlet 9 arranged at an intermediate point. That portion of the interior 60 of the tube below the outlet 9 is filled with plaster of Paris or other plastic material 10 in which is embedded a thermometer 11, the bulb 12 of which rests directly upon the bottom of the tube so that the heat from 65 the axle may readily conduct through the metal of the tube to the bulb for causing the mercury in the latter to expand for a purpose hereinafter described. Threaded into the upper end of the tube is a well known 70 form of oil cup 13 that communicates with the interior of the tube by way of a restricted passage 14. From this arrangement, it will be seen that oil dripping from the oil cup 13 will be deposited upon the upper 75 surface of the plaster of Paris from which it will pass into the annular chamber 8 by means of the outlet 9. Permanently in contact with the mercury in the column of the thermometer is the conductor 8' of the alarm 80 circuit 9' that includes an electric bell 10 and a battery 11, the other conductor of the circuit is hermetically sealed in the upper end of the column of the thermometer in such a manner as to have its ends disposed at a 85 predetermined distance above the surface of the mercury, as indicated at 16.

In the preferred form of my invention, I have shown a tube 17 resting upon the bulb of the thermometer, surrounding the column of the thermometer and passing through the side wall of the tube and communicating with the atmosphere, the object of this tube is to protect the circuit wires from the liquid within the tube. When it is 90 found advantageous in practice, the tube can be dispensed with and the mercury device or thermometer completely housed by the plaster of Paris in view of the fact that oil is practically a non-conductor of electricity having a very high resistivity.

From the foregoing description it will be seen that I combine an oil cup and a thermostatic circuit closer by means of which oil can be readily fed to a rotatable member and upon the stoppage of the flow of oil an alarm will be given.

Having described my invention, what I claim is:

In combination with a bearing, an axle 110

2,383,383
rotatably mounted therein, said bearing being provided with a bore communicating with said axle, a tube threaded in said bore and having a portion spaced from the wall 5 of the bore to form an annular chamber, the tube being provided with an opening to permit permanent communication with the chamber and the interior of the tube, plastic material arranged in the bottom of the tube

below said opening, and a thermostatic circuit closer supported by said plastic material. 10

In testimony whereof I affix my signature in presence of two witnesses.

JAMES E. CAMPBELL.
